BOBBIN RECEIVING AND GUIDING DEVICE FOR AUTOMATIC LOOMS

Original Filed July 20, 1933 2 Sheets-Sheet 2

UNITED STATES PATENT OFFICE

2,009,174

BOBBIN RECEIVING AND GUIDING DEVICE
FOR AUTOMATIC LOOMSAlbert A. Gordon, Worcester, Mass., assignor to
Crompton & Knowles Loom Works, Worcester,
Mass., a corporation of MassachusettsOriginal application July 20, 1933, Serial No.
681,272. Divided and this application November
15, 1934, Serial No. 753,187

4 Claims. (Cl. 139—255)

This invention relates to automatic looms of the bobbin changing type and is a division of my prior application Serial No. 681,272, filed by me July 20, 1933, which issued as Patent No. 1,982,249 on Nov. 27, 1934.

The general object of my invention as set forth in this divisional application is to provide an improved device for receiving and guiding the empty bobbins as they are ejected from the exhausted shuttles.

My invention further relates to arrangements and combinations of parts which will be herein-after described and more particularly set forth in the appended claims.

A preferred form of the invention is shown in the drawings, in which

Fig. 1 is an end view of parts of a loom, and showing the application of my invention thereto;

Fig. 2 is a front elevation of the device for directing and guiding the ejected bobbin;

Fig. 3 is an end view thereof, looking in the direction of the arrow 3 in Fig. 2, and

Fig. 4 is a detail plan view, looking in the direction of the arrow 4 in Fig. 2.

Referring to Fig. 1, I have shown portions of an automatic weft replenishing loom of the type shown in my prior patent and comprising a loom side 10, drop boxes 11, a two-cell magazine 12 and a transerrer 13 mounted on a rod or support 14 swinging about a fixed pivot 15.

A cam 16 is mounted on the usual cam shaft 17 and engages a cam roll 18 on a bell crank lever 19 mounted on a fixed pivot 20. A spring 21 holds the roll 18 yieldingly against the cam 16.

A stud 22 in the upper end of the bell crank 19 projects into an L-shaped slot 23 in a head 24 fixed to one end of a connecting rod or link 25, which in turn is pivoted at 26 to a collar 27 fixed on the transerrer support 14.

The head 24 rests on the outer end of an arm 30, mounted on a shaft 31 rotatable in fixed bearings and extending across to the other side of the loom where it has a feeler-controlled connection to intermittently actuated operating mechanism.

Under normal conditions, the parts occupy the position indicated in Fig. 1 and the stud 22 swings idly in the segmental horizontal portion of the slot 23. Upon indication of weft exhaustion, however, the arm 30 is swung upward when the stud 22 is at the front end of the slot 23, thus causing the stud to enter the vertical forward end portion of the slot 23 and to thereafter move the head 24, rod 25, support 14 and transerrer 13 rearward on the next oscillation of the bell crank 19 by the cam 16.

The magazine 12 is of the previously known type in which bobbin holders are selectively movable downward to present the lowermost bobbin B in the path of the transerrer 13. The movement of the bobbin holders is controlled by a rock shaft or so-called "color slide" 41 (Fig. 1) movable endways by a bell crank 42 to selectively engage the one or the other of the bobbin holders and movable angularly by the arm 43 and link 44 to depress the selected bobbin holder.

All of the parts thus far described are of the usual type as is also the operating mechanism for the feeler cross shaft 31, the bell crank 42 and the link 44.

A bobbin retaining device 45 (Fig. 1) is pivoted at 46 on the magazine frame and is provided at its lower end with a resilient plate 47 which yieldingly engages the bobbin B as the bobbin is moved rearward by the transerrer 13 in anticipation of transfer.

In looms of this type the pull-down connections to the harnesses commonly include a plurality of light wire rods 70 which extend downward just at the rear of the lay and more or less in the path of the ejected bobbins. Engagement of the wires by the ejected bobbins has been found objectionable.

It has also been found that properly retarding the rearward movement of the butt of the bobbin effects a rearward swinging movement of the tip 30 of the bobbin, which swinging movement is of substantial advantage in withdrawing the weft end upon the exhausted shuttle.

Accordingly I have provided the bobbin guiding and directing device 75 shown in detail in Figs. 2 to 4. This device comprises a box, preferably of sheet metal, having a contracted depending discharge portion 76 open at its lower end and having an open frame 77 in its upper front portion through which the ejected bobbins 40 enter the directing device.

The right-hand end of the device, as viewed in Fig. 2, is inclined forwardly, as indicated at 78 in Fig. 4, and is further provided with a forwardly and outwardly projecting wing or shield 45 79 positioned in front of the harness rods 70 and adapted to engage the butt of the empty bobbin B as the bobbin is ejected from the shuttle. Such engagement causes a turning movement of the bobbin, as indicated by the arrow 5 in Fig. 4.

This turning movement, as previously stated, is advantageous for withdrawing the weft end from the exhausted shuttle. The guiding and directing device 75 is mounted on a cross bar 55

80 which in turn is firmly attached to a suitable portion of the loom frame.

The device 75 and shield 79 thus act to protect the harness rods 70 and to cause a desired 5 turning movement of the ejected bobbin, as well as guiding the bobbins downward to the usual bobbin can or receptacle (not shown).

Having thus described my invention and the 10 advantages thereof, I do not wish to be limited to the details herein disclosed, otherwise than as set forth in the claims, but what I claim is:—

1. In a weft replenishing loom having a magazine and means to transfer bobbins substantially horizontally rearward from said magazine to a 15 shuttle on the lay and to simultaneously eject a bobbin rearward from said shuttle, a bobbin directing and guiding device at the back of the lay having the form of a container with an open front portion and with a bottom opening, one end 20 of said device being forwardly and outwardly inclined, and a shield projecting forwardly and outwardly from said inclined end and at one end of said open front portion, said shield being positioned for engagement by the butt of an ejected bobbin, whereby 25 the bobbin is directed point-first into said directing and guiding device.

2. In a weft replenishing loom having a magazine and means to transfer bobbins substantially horizontally rearward from said magazine to a 30 shuttle on the lay and to simultaneously eject a bobbin rearward from said shuttle, a bobbin directing and guiding device at the back of the lay having the form of a container with an open front portion and with a bottom opening, one

end of said device being forwardly and outwardly inclined, the top of said device being rearwardly and downwardly curved, and the lower portion of said device being contracted at the front and back and at one end toward said bottom opening. 5

3. In a weft replenishing loom having a magazine and means to transfer bobbins substantially horizontally rearward from said magazine to a shuttle on the lay and to simultaneously eject a bobbin rearward from said shuttle, 10 a bobbin directing and guiding device at the back of the lay having the form of a container with an open front portion, one end of said device being forwardly and outwardly inclined, and a shield projecting forwardly and outwardly from 15 said inclined end and at one end of said open front portion, said shield being positioned for engagement by the butt of an ejected bobbin, whereby the bobbin is directed point-first into said directing and guiding device. 20

4. In a weft replenishing loom having a magazine and means to transfer bobbins substantially horizontally rearward from said magazine to a shuttle on the lay and to simultaneously eject a bobbin rearward from said shuttle, a bobbin 25 directing and guiding device at the back of the lay having the form of a container with an open front portion, one end of said device being forwardly and outwardly inclined, the top of said device being rearwardly and downwardly curved, 30 and the lower portion of said device being contracted at the front and back and at one end toward the bottom portion of said device.

ALBERT A. GORDON.
